STARTER AND IGNITION MEANS FOR
TURBOJET ENGINESCurtis N. Lawter, Trenton, N. J., assignor to
Packard Motor Car Company, Detroit, Mich., a
corporation of Michigan

Application February 4, 1948, Serial No. 6,317

1 Claim. (Cl. 60—39.14)

1

The invention relates to a starting mechanism and ignition means for a turbo-jet engine, and the general object of the invention is to provide a simplified ignition system for a turbo-jet engine, utilizing a single more-or-less standard automotive type of distributor for supplying current to all of the spark plugs, instead of the individual vibrator for each plug heretofore employed.

It is also an object to provide a combined starting mechanism and ignition means under the control of a single switch.

Another object is to provide a combined starter and ignition means for a turbo-jet engine, which may be arranged to be used with any predetermined number of spark plugs and to energize each of such plugs any predetermined number of times per revolution of the starter shaft during the period of operation of the starter.

A further object is to provide a combined starter and ignition means for a turbo-jet engine, having a starter motor and distributor which may be constructed as a single unit with a drive shaft common to both.

Still another object is to provide a novel starter and ignition means for a turbo-jet engine, which may be made up of more-or-less standard automotive units modified to suit the requirements of a turbo-jet engine, thereby facilitating manufacture and reducing the cost of the structure.

Other objects and advantages will become apparent from the following description taken in connection with the accompanying drawing, in which:

Figure 1 is a diagrammatic front elevational view of a turbo-jet engine having a starter and ignition means embodying the features of the invention.

Fig. 2 is a side elevational view, partially in section, of one form of starter motor and distributor utilized in the starter and ignition means shown in Fig. 1.

Fig. 3 is a wiring diagram of the connections utilized in the means shown in Fig. 1.

Fig. 4 is a wiring diagram showing a modified arrangement of connections utilized in the distributor.

Fig. 5 is a view similar to Fig. 2 but showing a modified form of structure.

In a turbo-jet engine, where the turbine driven by the power stream generated within the engine is utilized to drive an air compressor for supplying air for combustion in the engine, an electric starting motor operated by battery current may be employed for starting the engine by rotating the shaft connecting the turbine and

2

air compressor up to the speed where operation of the engine is self-sustaining. In an engine of this character, the starter motor is operated to bring the turbine shaft up to a given speed before fuel is introduced into the combustion chamber section of the engine. After fuel is so introduced, the starter motor continues to exert its driving force since the engine has to be brought up to a still higher speed before it is self-sustaining in operation. During the period between these two speeds, part of the driving load is carried by the engine itself, but until the engine reaches the higher speed mentioned it is incapable of sustained operation. At such higher speed, the engine reaches the point where the starter motor may then be disconnected from the turbine-compressor shaft and stopped.

After the operation of the engine becomes self-sustaining, the heat in the combustion chamber is sufficient to ignite fresh fuel supplied to the burners therein without the necessity of utilizing any other ignition means. However, during the period from the time when fuel is first introduced into the combustion chamber until the self-sustaining speed is attained, an ignition means may be necessary. Such ignition means usually is in the form of a spark plug which may be similar in character to that utilized in automotive engines. It is thus apparent that the ignition means should operate during such period and may be shut off or dispensed with at the time that the starter motor is disconnected from the turbine-compressor shaft. Consequently, the operation of the ignition means may be contemporaneous with the operation of the starter, and the starter and ignition means may, therefore, be under the control of a single control element.

With a turbo-jet engine which is provided with more than one combustion chamber, a spark plug may, of course, be provided in each such chamber. If, however, only one combustion chamber is provided, such as an annular combustion chamber, at least one spark plug must be used, but a plurality of spark plugs may be, and preferably are, used so that the fuel will be ignited at more than one point therein. It is also desirable to effect operation of such spark plugs with as great frequency as possible in order to approach a condition of constant ignition since the supply of fuel to the combustion chamber is constant.

Since the ignition system need be operated only contemporaneously with the starter and, therefore, may be under the same control as the starter, as stated above, a distributor for energizing the spark plugs in the combustion chamber

section of the engine may be driven by the starter motor. The distributor as well as an ignition coil utilized in a system of this character may, therefore, be constructed as a unit with the starter motor. The distributor may be generally similar to the automotive type of distributor.

Referring to the drawings, in Fig. 1 a turbo-jet engine is diagrammatically shown at 10 and is provided with a plurality of spark plugs 11, two spark plugs being shown in the present instance. The engine may be provided with a gearbox 12 containing gearing connected to the turbine air-compressor shaft of the engine. An electrical starting motor 13 may be mounted on the gearbox 12 and be provided with a clutch connection 14 (see Fig. 2) adapted to disconnect the shaft of the starter motor 13 from the gearing when the motor tends to overrun the gearing. Such mode of connection of a starter motor with an engine is usual in automotive practice. As indicated in Fig. 3, the starter motor 13 is provided with field coils 15 connected by lines 16 and 17 to opposite poles of a battery 20. The motor 13 is under the control of a switch which is herein shown at 21 in the line 16. The shaft of the motor in Figs. 2 and 3 is shown at 22. One pole of the battery 20 may be grounded as at 23.

The ignition means, which includes the spark plugs 11, in addition comprises an ignition coil, indicated generally at 24, and a distributor, indicated generally at 25. The ignition coil 24 comprises a primary winding 26 adapted to be connected to one pole of the battery with the other side of the winding grounded, and a secondary winding 27, one side of which is grounded. The other side of the secondary winding 27 is connected to the distributor, as will be hereinafter described.

As mentioned above, one of the features of the invention lies in placing the ignition system under the same control as the starter motor 13. To this end, the connection of the primary winding 26 of the ignition coil to the battery is by means of a line 30 connected to the line 16 for the motor 13 so that flow of current to the primary winding is thus subjected to the control of the switch 21, which also controls operation of the motor 13. The distributor 25 comprises a plurality of contact points adapted to be connected to the spark plugs 11 and a rotor connected to one side of the secondary winding 27 of the ignition coil 24, the contact points being arranged in a circle and adapted to be sequentially connected to the secondary winding of the ignition coil by rotation of the rotor. In the present instance, the distributor 25 is illustrated as being provided with two contact points 31 connected by lines 32 to the spark plugs 11. The rotor of the distributor is shown at 33 and is connected to the secondary winding 27 by a line 34. The spark plugs, of course, are grounded to complete the circuit therethrough. Since the ignition coil 24 is operable only while the motor 13 is operating because of the single control switch 21, the distributor 25 need only operate during this period. For this reason, the rotor 33 may be operated by the motor 13 and, consequently, may be carried on the motor shaft 22. As is usual in the case of an ignition coil operating in connection with a battery, the circuit through the primary winding 26 of the ignition coil is interrupted just before the rotor 33 contacts one of the contact points 31 so as to produce a fluctuation of current in the primary winding 26 which may be transformed by the secondary winding 27. To this end, the dis-

tributor also includes a breaker switch 35 adapted to be opened by means of a cam 36, the cam 36, similarly to the rotor 33, may be carried on the motor shaft 22. A condenser 37 is preferably connected in parallel with the switch 35, as is customary in devices of this character. The breaker cam 36 is adapted to open the switch 35 just before the rotor 33 moves into engagement with each of the contact points 31. Consequently, with two such contact points as shown in Fig. 3, the breaker cam will be provided with two lobes 40 to open the switch 35.

With the foregoing structure, it will be obvious that when the switch 21 is closed to operate the starter motor 13, current also will be supplied from the battery 20 to the primary winding 26 of the ignition coil 24 by the line 30. Rotation of the motor shaft 22 at such time operates the breaker cam 36 and the rotor 33 of the distributor so that high-tension current is supplied alternately to the two spark plugs 11 to produce sparks therein and ignite the fuel in the combustion chamber section of the engine 10. When the engine reaches such speed as to become self-sustaining and the starter is no longer needed, then the switch 21 may be opened to stop the starter motor, the clutch 14 thereof automatically disconnecting from the gearing in the gearbox 12 at such time. Simultaneously with the stopping of the starter motor 13, the current to the primary winding of the ignition coil 24 is cut off and rotation of the rotor 33 of the distributor as well as rotation of the breaker cam 36 is stopped. Consequently, when the starting motor 13 is stopped and disconnected from the engine, supply of high-tension current to the spark plugs 11 ceases.

In a broad sense, of course, supply of high-tension current to the spark plugs 11 may be stopped merely by opening the single control switch for the starter motor, whether or not the distributor is driven by the starter motor. Thus, if the starter motor were driven from some other source of power, for instance by the engine itself, the rotor 33 would continue to rotate but no current would be supplied to the spark plugs since the switch 21 would cut off the supply of current from the battery 20 to the primary winding of the ignition coil 24. The same broad result could also be obtained by having separate switches controlling the flow of current from the battery to the starting motor and to the primary winding of the ignition coil 24, if the distributor were mounted on the starter motor shaft, as shown in the drawings. In that instance, even though current continued to be supplied from the battery to the primary winding 26 after the starter motor was stopped, neither the breaker cam 36 nor the rotor 33 would operate in that case and, consequently, no high-tension current would be supplied to the spark plugs 11. It is preferred, however, to utilize the arrangement shown diagrammatically in Fig. 3, where a switch common to both the starting motor and the ignition coil is employed and the distributor is driven by the starting motor.

As heretofore mentioned, if the turbo-jet engine has a plurality of combustion chambers, then at least one spark plug may be provided for each such chamber to ignite the fuel therein, although in some instances only certain of the chambers are provided with spark plugs and the fuel in the other chambers is ignited through the use of transfer passages connecting the chambers. However, if the combustion chamber is annular

in form and is coaxial with the engine so that the combustion chamber is relatively large, it may be desirable to utilize more than one spark plug for the single chamber, so that ignition of fuel takes place at more than one point in such chamber. The arrangement shown in Figs. 1 and 3 of the drawings, since two contact points 31 are shown and only two spark plugs 11 are employed, is such that it may be used either with an engine having separate combustion chambers or a single chamber with two points of ignition therein. Since fuel is supplied constantly to the engine after it reaches a predetermined speed, it, of course, would be desirable to have a constantly or continuously operating ignition means. While the present system would not permit of such constant operation, since the source of current is a battery which requires interruption to obtain higher voltage by inductive means, an approach to constant operation may be attained by an arrangement illustrated diagrammatically in Fig. 4. In Fig. 4 I have shown a distributor 50 provided with a plurality of contact points 51, in the present instance eight such contact points being shown. Such a distributor may be utilized with a plurality of spark plugs where the number of spark plugs is less than the number of contact points 51 but the latter number is a multiple of the number of spark plugs. With this arrangement, the contact points are consecutively connected to the respective spark plugs so that at least two non-adjacent contact points are connected to each of the spark plugs. Thus, with the distributor shown in Fig. 4 utilized with two spark plugs as shown in Fig. 1, alternate contact points 51 are interconnected by the lines 52 and are then connected to one of the spark plugs 11 by a single line 53. The remaining contact points 51 are interconnected by the lines 54 and are connected to the other spark plug 11 by a line 55. With only two contact points, such as the contact points 31 shown in Fig. 3, a spark will be produced in each spark plug 11 only once for each revolution of the starting motor. With the arrangement shown in Fig. 4, a spark will be produced in each spark plug 11 four times for each revolution of the starting motor. Operation of the spark plugs 11 thereby becomes more frequent and approaches the constant ignition condition mentioned above.

By placing the ignition coil under the control of the same switch for the starting motor and by operating the distributor from the shaft 22 of the starting motor, the distributor and starter motor may be combined in a single unitary structure, as disclosed in Fig. 2. Thus, in this instance, the motor 13 is provided with a frame including an end cap 60, on which the distributor cover 61 may be mounted. Further unification of the

structure may be attained by making the ignition coil in the form of a pancake, as indicated at 62, and enclosing it within a portion of the cover 61. In Fig. 5, I have shown a slightly different form of distributor, here shown at 63, mounted on the cover 60 of the motor frame. The ignition coil in this instance may be separate from the distributor and may be mounted directly on the motor 13, as indicated at 64. In both of the forms shown in Figs. 2 and 5, the distributor rotor 33 as well as the breaker cam 30 are carried on the motor shaft 22.

I claim:

The combination of a turbo-jet engine having a plurality of fuel burners and a centrally disposed rotatably mounted drive shaft and a unitary starter and ignition means for said engine including a plurality of spark plugs cooperating with the burners to initiate a burning of the fuel in the engine, comprising a starter motor having a frame and a drive shaft, said shaft being adapted to be detachably connected to the turbine shaft of the engine, a distributor mounted on said frame coaxially with said drive shaft, a rotor in said distributor, said rotor being carried by said shaft, an ignition coil, a battery connected to said coil, a series of contact points in said distributor that are adapted for cooperation with said rotor, the number of said points in said series being a multiple greater than one of the number of spark plugs with at least two of said contact points being electrically connected to each of said spark plugs, the connections between each of the spark plugs and said series of contact points being swept by the rotor being consecutively arranged so that adjacent points are connected to different plugs, and said distributor being operably connected to said battery and coil whereby the plugs connected to said series of contact points may be consecutively caused to spark a plurality of times during each revolution of the rotor.
